UNITED STATES PATENT OFFICE.

JACOB SIEM, OF HOMBURG-VOR-DER-HÖHE, GERMANY.

FORCING-FRAME.

SPECIFICATION forming part of Letters Patent No. 374,499, dated December 6, 1887.

Application filed April 26, 1887. Serial No. 236,192. (No model.)

To all whom it may concern:

Be it known that I, JACOB SIEM, a subject of the Emperor of Germany, residing at Homburg-vor-der-Höhe, Germany, have invented 55
5 new and useful Improvements in Forcing-
Frames, of which the following is a specifica-
tion.

This invention relates to means for produc-
ing and maintaining the heat of hot-beds for
10 horticultural purposes by means of hot water.
The advisability of warming hot-beds by arti-
ficial heat instead of manure has already given
rise to many experiments in this direction,
but hitherto with unsatisfactory results, the
15 heat having invariably been unequally and
irregularly distributed over the bed. Accord-
ing to the present invention these defects are
obviated by arranging a hot-water reservoir
20 below the bed, in which reservoir, by a pecu-
liar arrangement of the inlet and outlet pipes,
the water heated in a boiler outside continu-
ally circulates in such a manner that the entire
surface has a uniform temperature.

Reference is to be had to the accompanying
25 drawings, forming part of this specification,
in which similar letters of reference indicate
corresponding parts in all the figures.

Figure 1 is a plan view of the forcing-frame,
the glass cover being removed and the bottom
30 of the earth-receptacle partly broken away.
Fig. 2 is a cross-section on the broken line *x*
x, Fig. 1. Fig. 3 is a like section on line *y*
y, Fig. 1. Fig. 4 is a longitudinal section on
line *z* *z*, Fig. 1.

35 The water-reservoir *a a*, which is advanta-
geously constructed of cement, is covered by
thin cement plates *b b*, which form the bottom
of the earth-receptacles of the bed. These
cement plates *b b* rest upon cement columns *c*
40 in the water-reservoir *a a*. The reservoir *a a*
is divided by a vertical partition, *e*, into two
compartments which communicate with each
other through pipes, hereinafter described,
the said partition extending from the bottom
45 of the reservoir to near the top of the earth-
receptacle, and dividing it also into two com-
partments. In front of the reservoir, below
the level of the same, is placed a small circu-
lating-boiler, *m*, which serves to heat the
50 water in the reservoir *a a*, and to maintain it
at the desired degree of heat. A pipe, *f*, con-

veys the hot water from the upper end of the
boiler *m* through the first compartment di-
rectly into the second compartment, the hot
water flowing through the said pipe giving up 55
a portion of its heat to the water in the first
compartment. A second pipe, *g*, passing along
the transverse rear wall and one side wall of
the second compartment, and then also along
one side wall of the first compartment, con- 60
veys the water which is in proximity to the
back wall of the second compartment into
proximity to the transverse front wall of the
first compartment—that is to say, from *h* to *i*.
A third pipe, *w*, passes through the transverse 65
back wall of the first compartment at *k* to
near the back wall of the second compartment,
thence back again through the second com-
partment, and then through the rear wall of
the first compartment, and through the said 70
first compartment to the lower end of the cir-
culating-boiler *m*. By means of this system of
pipes a good circulation of the water is main-
tained and a uniform temperature at all points
of the reservoir is insured. 75

On the outside of the reservoir is a small
channel, *n*, which is in communication with
the said reservoir *a a* through a short passage,
l. This channel serves for filling the reser-
voir at the beginning of the operation, the air 80
contained in the reservoir being able to escape
through suitable rising pipes, *o*. This chan-
nel *n* has a vent provided with a plug, (see
Figs. 1 and 2,) so that the reservoir can be
emptied by removing the plug. The rising 85
pipes *o* extend from the top of the reservoir *a a*
to near the top of the bed or earth-receptacle
s to form passages for the escape of air when
the reservoir is being filled, and also to permit
steam to rise therethrough against the glass 90
cover and there condense and fall on the earth,
keeping it moist and preventing it from be-
coming hard and dry. Should the tempera-
ture rise beyond the desired degree, the burn-
ing of the roots can be obviated by tempo- 95
rarily letting off part of the water through
the channel. The water then recedes slightly
from the cement top of the reservoir. It is,
however, essential, under ordinary circum-
stances, that the heating water should touch 100
the top of the reservoir *a a*—that is to say, of
the lower surface of the cement plates *b*. This

condition can be maintained by means of the said channel *n*.

Openings *p p* are formed in the side walls of the forcing-frame above the water-reservoir, 5 and in front of which glasses are fixed in the cement wall, as shown in Fig. 3. These openings serve to receive thermometers, the scale of which is visible through the glasses, the said thermometers indicating the temperature 10 of the water in the reservoir. This arrangement is very suitable during severe cold, when it is not desirable to open the frames to let down the thermometers through the rising pipes.

15 In order that a tight joint shall always be formed around the circulating-pipes *f* and *w*, which pass through the front wall of the reservoir, a sheet of lead, *z*, is placed perpendicularly in this front wall and connected by soldering with the said circulating-pipes.

The bottom and side wall of the reservoir are isolated from the soil by wooden planks *r*, or by any other material that does not conduct heat.

25 *V* indicates the glass top, which in practice will be set in several frames in the usual manner.

In the upper surface of the cement plates *b*, that separates the hot-bed from the hot-water reservoir, is formed a series of grooves, 30 *a'*, the said grooves registering with apertures *a* in the side walls of the forcing-frame to conduct outward any surplus of moisture in the hot-bed *s*.

35 As stated at the commencement of this specification, trials have already frequently been made to artificially heat hot-beds. Usually, however, an air-space has been formed beneath the supports of the bed, so that powerful heating is required in order that the earth above shall be warmed. By heating in this manner it is altogether impossible to prevent the earth from becoming dry or even from burning. Heated water has also been used 40 below the beds, the vapors rising from the water being employed to effect the heating of the earth; but such vapors have conveyed too much moisture to the earth, thereby injuring the growth of the plants, apart from other disadvantages which have shown themselves.

45 The present invention differs essentially from the means heretofore employed in the fact that the water-reservoir is tightly covered at the top with cement plates, the hot water being

in contact with the lower surfaces of these 55 plates. Now, as the mold to be heated rests upon these plates, which are very uniformly heated, the said mold will also be heated in the most uniform and beneficial manner without moisture from the heating water coming 60 into contact with the mold.

A bed heated in the manner before described can be used for raising plants and forcing flowers and vegetables. It can also be used to heat the ground for pot-plants which 65 are in the open air, and for warming the ground for forcing-houses.

Having thus described my invention and the manner of employing the same, what I claim, and wish to have secured to me by Letters Patent of the United States of America, 70 is—

1. The combination, with the cement reservoir having the columns *c* in its bottom, the filling-channel *n* at the side thereof, and a central transverse division-plate, *e*, forming two compartments, of a cement plate, *b*, at each side of said division plate and resting on the columns, and supply and outlet hot-water pipes leading into and through said compartments, 75 substantially as set forth.

2. A forcing-frame having side apertures, *a*, a hot-water reservoir in its bottom, a bed or receptacle above the same, and cement plates separating the said reservoir from the 80 receptacle and provided with grooves *a'* on the upper surfaces registering with the apertures *a*, substantially as set forth.

3. A forcing-frame constructed with a hot-water reservoir in the bottom having two compartments, in combination with the inlet-pipe *f*, passing through the first compartment and into the forward part of the second compartment, the pipe *g*, extending from the rear part of the second compartment to the forward 90 part of the first compartment, and the outlet-pipe extending from the rear of the first compartment to the rear part of the second compartment and back through the first compartment, substantially as shown and described. 95

In testimony whereof I have signed my name to this specification in the presence of two subscribing witnesses.

JACOB SIEM.
